TABLE UNIT

Raymond H. Ovendale, Alhambra, Calif.

Application July 2, 1951, Serial No. 15,734

Term of patent 7 years

(Cl. D33—14)

To all whom it may concern:

Be it known that I, Raymond H. Ovendale, a citizen of the United States of America, residing in Alhambra, county of Los Angeles, and State of California, have invented a new, original, and ornamental Design for a Table Unit, of which the following is a specification, reference being had to the accompanying drawing, forming part thereof:

Fig. 1 is a perspective view of a table unit, showing my new design.

Fig. 2 is a top plan view thereof.

The dominant features of the design are shown in full lines in the drawing.

I claim:

The ornamental design for a table unit, substantially as shown and described.

RAYMOND H. OVENDALE.
